CLAIM

The ornamental design for a foldable fabric storage box, as shown and described.

DESCRIPTION

FIG. 1 is a front perspective view of a foldable fabric storage box showing my ornamental design;

FIG. 2 is a rear perspective view of a foldable fabric storage box showing my ornamental design;

FIG. 3 is a front view of a foldable fabric storage box showing my ornamental design;

FIG. 4 is a rear view of a foldable fabric storage box showing my ornamental design;

FIG. 5 is a left side view of a foldable fabric storage box showing my ornamental design;

FIG. 6 is a right side view of a foldable fabric storage box showing my ornamental design;

FIG. 7 is a top view of a backpacking foldable fabric storage box my ornamental design;

FIG. 8 is a bottom view of a backpacking foldable fabric storage box my ornamental design.

FIG. 9 is a front perspective view thereof, shown with the foldable fabric storage box in a partially opened configuration;

FIG. 10 is a front perspective view thereof, shown with the foldable fabric storage box in a flattened, opened configuration; and,

FIG. 11 is an enlarged view of a foldable fabric storage box showing my ornamental design labeled FIG. 11 in FIG. 9.
